UNITED STATES PATENT OFFICE

101,683

DESIGN FOR A COAT OR SIMILAR ARTICLE

Samuel Rosenblatt, New York, N. Y.

Application August 25, 1936, Serial No. 64,566

Term of patent 3½ years

To all whom it may concern:

Be it known that Samuel Rosenblatt, a citizen of the United States and resident of New York city, in the county of New York, State of New York, has invented a new, original, and ornamental Design for a Coat or Similar Article, of which the following is a specification, reference being had to the accompanying drawing forming part thereof, and in which,

Fig. 1 is a front view of a coat embodying my new design; and

Fig. 2 is a rear view of the same.

I claim:—

The ornamental design for a coat or similar article substantially as shown.

SAMUEL ROSENBLATT.
